UNITED STATES PATENT OFFICE.

HENRY FRANCIS KEIL, OF NEW YORK, N. Y.

PLATE-GLASS STRUCTURE.

1,107,671.

Specification of Letters Patent. Patented Aug. 18, 1914.

Application filed June 20, 1913. Serial No. 774,936.

To all whom it may concern:

Be it known that I, HENRY FRANCIS KEIL, a citizen of the United States of America, and a resident of New York, in the county of New York and State of New York, have invented a certain new and useful Plate-Glass Structure, of which the following is a specification, the same being a full, clear, and exact description of the invention, such as will enable others skilled in the art to which it appertains to make and use the same.

This invention relates to articles designed for purposes of exhibition, as a case or enclosure of which all or some of the sides are of glass, intended to keep small and delicate or valuable objects from dust and injury while leaving them in plain sight, and in particular to means for holding the glass plates together by means of metallic corner pieces and of providing the same with means for preventing the same from working loose, which metal pieces may be clamped to the plate glass sides of the show case at the corners thereof, and whereby the plate glass top or cover may be also rigidly and immovably secured to the said show case.

With this object in view the invention consists in certain novel features of construction and arrangement of parts.

In order to enable the invention to be fully understood, I shall proceed to explain the same by reference to the drawings illustrative of one embodiment of the invention, which accompany and form a part of this specification, and in which—

Figure 1 is a plan view of an article in which my invention is embodied; Fig. 2 is an elevation of the same; and Figs. 3, 4, 5, 6 and 7 are views in detail showing the construction of the various parts of the invention.

Like letters of reference indicate like parts in all the views.

Referring particularly to the drawings which represent a show case which may be of any ordinary or suitable and approved construction, A denotes the front glass plate thereof, A' and A² the side plates, A³ the top and A⁴ the base of the same, the show case in the present instance being also provided with a wooden back A⁵ of ordinary construction.

In order to hold the glass plates together in angular abutment suitable and approved clamping devices may be used such, for example, as the metal corner pieces B having

a slidable top member b working in a groove b² formed in the part B, the top piece b being secured in place as by a screw b⁴ adjustable within the show case. The rear plates 60 may be likewise held together as by means of clamps B' also having a top member b' working in a groove b³ formed in the part B', the top piece b' being secured in place by a screw b⁵. Strips of felt D may be inserted between the metal clamps so as to lie between the vertical and horizontal glass plates.

In the use of glass show cases that are made of plate glass, the various sections of which are clamped together it has been found, as for example where the cases are frequently moved about, that the clamping devices often work loose after a time as the same bear directly against the smooth face 75 of the glass. In order to remedy this defect and to endeavor to permanently retain the clamping devices in operative position orifices are frequently bored through the plate glass which orifices serve to contain 80 bolts, but this method involves some extra expense and moreover is detrimental to the glass, as the latter becomes so weakened thereby that upon any undue strain or stress occurring at the point where the hole is located, the glass is apt to become broken, 85 owing to the necessary proximity of the said orifice to the edge of the glass.

In order to overcome these difficulties and to permanently retain the clamping devices 90 in their normal operative positions I make a small indentation a in the glass plate on the inner face of the same, the said indentation being ordinarily curved in contour such as is ordinarily known as a countersink. I 95 then insert a screw as C through the clamping device within the show case so that the preferably rounded point of the same will register with and enter the said indentation. The outer part of the clamping device forms 100 a rest or bearing for the glass plate which bearing prevents any undue tension upon the glass when the screw C is operated so that there is no danger of the glass becoming broken, while at the same time the said 105 screw C rigidly holds the clamping device from working in a lateral direction or from any movement whatsoever. As many indentations a and coöperating screws C may be used as is deemed desirable, and the said 110 clamps may be employed not only in connection with the particular clamping device

shown and described, but also with any other of the clamping devices used in connection with articles of the character set forth.

5 Although in the embodiment shown the positioning means attached to the clamping device is only adapted to be used with a square or rectangular show case, yet it is manifest that the invention may be easily 10 adapted to show cases of other forms and contours by those skilled in the art.

I wish it to be understood that I do not desire to be limited to the exact details of construction shown and described, for obvious 15 modifications will occur to persons skilled in the art.

What I claim is:—

In a device of the class described, a corner member having a central body portion 20 and a channel formed by parallel depending flanges to receive the side abutting plates, projections located in the inner part of the member and indentations formed in the side

plates to register therewith to hold the plates from lateral movement, in combination with another corner member the top of which covers the top plate and the lower part whereof is flush with the top face of the first member, and adjustable means located at the interior corner of the show case to engage both of the said members whereby, by the operation thereof alone, the projections may be forced with an outward pressure against the indentations in the side plates and the top plate may be held to the side plates with an inward pressure, the pressure being distributed along the faces of all of the plates in lieu of being localized.

In testimony of the foregoing specification I do hereby sign the same in the city of 41 New York, county and State of New York, this 21st day of May, 1913.

HENRY FRANCIS KEIL.
